(57) **CLAIM**

The ornamental design for an endoscope, as shown and described.

DESCRIPTION

FIG. 1 is a perspective view;

FIG. 2 is an enlarged partial perspective view;

FIG. 3 is a front view of an endoscope showing our new design;

FIG. 4 is a rear view thereof;

FIG. 5 is a plan view thereof;

FIG. 6 is a bottom view thereof;

FIG. 7 is a right side view thereof;

FIG. 8 is a left side view thereof;

FIG. 9 is an enlarged partial left side view of 11-11 section of FIG. 3;

FIG. 10 is an enlarged partial view taken along line 11-11 of FIG. 3;

FIG. 11 is an enlarged partial view taken along line 12-12 of FIG. 4;

FIG. 12 is an enlarged partial view taken along line 13-13 of FIG. 5;

FIG. 13 is an enlarged partial view taken along line 14-14 of FIG. 6;

FIG. 14 is a view from line 15-15 of FIG. 10;

FIG. 15 is a sectional view which is omitted internal mechanism and is taken along line 16-16 of FIG. 14;

FIG. 16 is a sectional view which is omitted internal mechanism and is taken along line 17-17 of FIG. 14; and, FIG. 17 is a sectional view which omits internal mechanism and is taken along line 18-18 of FIG. 14.

The details outlined in dashed broken lines depict unclaimed portions of the endoscope and form no part of the claim. The dash-dot-dash lines disclose the boundary of the claim and
